CLAIM

The ornamental design for a nozzle unit as shown and
described.

DESCRIPTION

FIG. 1 is a perspective view of a first embodiment of a
nozzle unit showing my new design;
FIG. 2 is a perspective view thereof;
FIG. 3 is a top view thereof;
FIG. 4 is a front side view thereof;
FIG. 5 is a left view thereof;
FIG. 6 is a rear side view thereof;
FIG. 7 is a bottom view thereof;
FIG. 8 is a left view thereof;
FIG. 9 is a sectional view thereof;
FIG. 10 is a perspective view of a second embodiment of a
nozzle unit showing my new design;
FIG. 11 is a perspective view thereof;
FIG. 12 is a top view thereof;
FIG. 13 is a front side view thereof;
FIG. 14 is a left view thereof;
FIG. 15 is a rear side view thereof;
FIG. 16 is a bottom view thereof;
FIG. 17 is a left view thereof; and,
FIG. 18 is a sectional view thereof.

1 Claim, 18 Drawing Sheets

Related U.S. Application Data

which is a continuation of application No. 15/741,905, filed as application No. PCT/EP2016/065936 on Jul. 6, 2016, now Pat. No. 11,090,665, application No. 29/812,456 is a continuation-in-part of application No. 17/375,073, filed on Jul. 14, 2021, now Pat. No. 11,772,107, which is a continuation of application No. 15/741,905, filed as application No. PCT/EP2016/065936 on Jul. 6, 2016, now Pat. No. 11,090,665.
